Clemir J. Ney, of Lowell, Mass.

Assignor to

Lowell Manf. Company, of same place.
Letters Patent No 3 dated Feb. 5 1861.

Whole No. 1368.

The schedule referred to in these Letters Patent and making part of the same.

To all whom it may concern:

Be it known that I, Clemir J. Ney, of Lowell, in the County of Middlesex, and State of Massachusetts, have originated and designed a new Pattern for Carpets or other fabrics, of which the following is a full, clear and exact description, reference being had to the accompanying drawings, making part of this specification.

A. is a spotted ground surrounded by leaves and branches, 1. corners, 2 and 3, and side figure B, when matched form a ground composed of small diamonds and surrounded by branch work 4. Corners 5 and 6, and side figure C, when matched form another ground composed of diamonds and surrounded by branch work. D, and E, at sides, when matched form a 12 pointed block supporting scroll work 7. F, and G, at sides form another block, similar to that of D and E. Connecting figs. D, and E, are broad bands 8.8, composed of mottled and key work. Connecting F, and G, are similar bands 9.9, crossing the bands 8.8, at right angles.

Between figs. D, and E, lies the group of leaves and flowers H.

The colors employed for the different portions of the design may be varied to suit the taste and wish of the manufacturer.

Claim.

What I claim as my invention, and desire to secure by letters patent is the design or pattern for Carpets or other fabrics herein set forth.
